M. G. KOURY

DOUBLE ACTING INTERNAL COMBUSTION ENGINE

Filed Nov. 6, 1925

UNITED STATES PATENT OFFICE.

MICHAEL G. KOURY, OF CAIRO, ILLINOIS.

DOUBLE-ACTING INTERNAL-COMBUSTION ENGINE.

Application filed November 6, 1925. Serial No. 67,319.

This invention relates to improvements in double acting internal combustion engines and particularly to an engine of this character employing a single piston construction 5 and a rotary valve mechanism.

An object of the invention resides in providing a double acting internal combustion engine having a special piston construction and a rotary valve mechanism for controlling the inlet and the exhaust to the opposite ends of the cylinder acting on said piston structure in order to produce four cycle engine of simple construction and embodying relatively few constructional parts, at 15 the same time showing efficient operation.

A further object of the invention resides in providing a double acting internal combustion engine having a crank case structure formed with a guide for the cross head and 20 also provided with a head construction for one end of the cylinder against which the cylinder body is mounted to be assembled together with the head structure for the opposite end of the body, which part is secured 25 in assembled relation by single assembling means.

The invention comprehends numerous other objects and improvements in the details of construction and arrangement of 30 parts which are more particularly pointed out in the following detailed description and in the claims directed to a preferred form of the invention, it being understood, however, that various changes may be made in the 35 size, shape, arrangement and assembly of the parts which are entirely within the scope of the invention as herein set forth.

In the drawing forming part of this application—

40 Figure 1 is a vertical transverse sectional view through the improved internal combustion engine structure, showing one cylinder construction in the valve structure associated therewith.

45 Fig. 2 is an enlarged detail view of the piston structure having portions shown in section.

50 Fig. 3 is a transverse sectional view through the piston rods and the pressure feed outlet for feeding oil to the hollow piston rods for supply to the piston structure.

55 Fig. 4 is a vertical sectional view through the rotary valve body showing the detailed construction thereof.

A crank case structure is indicated at 1 which forms a main supporting body for the engine and is adapted on a suitable support in any well known and desired manner and on the bottom of which is secured the 60 cover or oil pan 2 for entirely closing and housing the parts of the engine mounted within the crank case structure. The upper end of this crank case structure is formed with a head portion 3 spaced for receiving the cylinder block 4 which is spaced at the 65 opposite end for receiving the head structure 5. These elements are adapted to be assembled in the manner shown in Fig. 1, and secured in the assembled relation by the 70 bolts 6 forming the main assembling means for the engine structure so that the cylinder blocks 4, the head 5, and the crank case structure 1 are secured in assembled relation 75 by these bolts 6 during the normal operation of the engine.

The cylinder block 4 is formed with a cylinder 7 extending entirely through the block and opening at both ends thereof around which is the cooling jacket 8 for a 80 suitable cooling medium such as water or the like. This cylinder 7 is formed in one side of the block, while on the opposite side of the block is formed a cylindrical bore at 9 providing a valve housing for the rotary valve 85 structure 10. Ports 11 are formed in the opposite ends of the cylinder blocks establishing communication between the cylindrical bore and the cylinder 7, while the outer wall of the valve housing is provided with an exhaust passage 12 and inlet passages 13 over which is mounted a suitable inlet and exhaust manifold not shown in the drawing. The rotary valve 10 is of cylindrical form and is provided with a pair of exhaust passages 14 extending diagonally through the body of the valve for establishing communication alternately between the cylinder 7 and the exhaust outlet 12 through the ports 11 at the opposite ends thereof.

100 These exhaust passages of the rotary valve structure are arranged at substantially right angles with respect to one another while in angular relation with these exhaust passages, are arranged other passages indicated at 15 which are also in angular relation with one another for establishing communication between the inlet openings 13 and the ports 11 for controlling the inlet of the gaseous mixture to the cylinder 7. 110

This rotary valve 10 is provided with a reduced cylindrical extension 16 at the upper end mounted in the bearing structure 17, carried by the cylinder head 5 and providing a bearing for the upper end of the cylindrical body. A cooling jacket 18 is formed in the head structure 5 surrounding this bearing structure 17 for preventing the same from becoming overheated. The lower 10 end of the cylindrical valve stem is formed with a shaft extension 19 extending through a cylindrical bore in the crank casing structure 1 and the head portion 3 thereon and is mounted in the bearing 20 in the head portion 3 adjacent the lower end of the valve body while the lower end of the shaft is mounted in the bearing structure 21 carried by the crank case structure. This provides a uniform bearing structure for the 20 rotary valve 10 to insure its efficient operation at low friction and yet permit the efficient control of the ports 11 for the intake and exhaust at the opposite ends of the cylinder 7.

25 The lower ends of the shafts 19 is provided with a beveled gear 22 intermeshing with the rotary driven valve timing gearing 23 which is driven by the gear 24 from the gear 25 on crank shaft 26 of the engine. 30 This valve driving gearing 23 in the form shown in Fig. 1 of the drawings, may be utilized for driving rotary valves for other cylinders of a multiple cylinder engine of the type shown in Fig. 1, the remaining 35 structure of the cylinders being the same as that shown from the single cylinder structure illustrated.

The crank shaft 26 is formed with the usual crank 27 with which is secured the 40 connecting rod 28 having the opposite end provided with a bearing 29 in the cross head 30. The cross head 30 is provided with guides 31 within the crank case structure 1 and the piston rods 32 has one end thereof 45 removably secured to the cross head. This piston rod extends through the bearings 33 and 34 of similar constructions provided in the head portion 3 and the head structure 5 which bearings are formed with a plurality of grooves for receiving compression 50 rings adapted to be normally contracted for engaging the surface of the piston rod and form a gas-tight joint therewith to prevent the leakage of gas from the opposite ends of the cylinder 7.

In the central portion, the piston 32 is provided with a portion of enlarged diameter at 35 at one end of which is formed the annular flange 36 while at the opposite end 60 is formed a threaded portion 37. The enlarged portion 35 is substantially cylindrical but tapers slightly from the end of the flange 36 toward its threaded end for receiving the piston 38 provided with a slightly tapering opening adapted to fit the por-

tion 35 so that the flange 37 is received within its recess 39 in one end of the piston. The opposite end of the piston is formed with a recess 40 for securing the ring 41 adapted to be threadedly mounted on the threads 37 for rigidly securing the piston on the piston rod. 70

The periphery of the piston 38 is formed with the usual ring grooves, and in the central portion is formed with an oil groove 75 42 with which communicates a plurality of radially extending ducts 43 communicating with the inner oil groove 44 supplied with oil through the ducts 45 in the piston rod from the passage 46 extending longitudinally of the piston rods as clearly illustrated in Fig. 1. In the portion of the piston rod which is normally within the crank case 80 1 is formed a seat duct 47 communicating with the oil passage 46 and in one position 85 preferably, at the upper end of the stroke of the piston of this piston rod 32 this feed duct 47 communicates with the oil feed heads 48 having a track bearing face 49 riding on the surface of the piston rod 32 90 so that oil from a suitable source or feed pump may be discharged through the conduits 50 and the head 48 into the oil passage 46 to be fed to the oil groove 42 of the piston and cooperate with the piston rings 95 to form a seal to prevent the leakage of gas passed the piston.

The head 43 is formed at 51 with a threaded opening extending from the edge portion into the end portion of the head at the end 100 of the cylinder 7 and providing a spark plug opening for the spark plug 52. The head structure 5 is also formed with a spark plug opening 53 for receiving the spark plug 54 adapted to ignite the charge 105 in the opposite end of the cylinder 7 from the spark plug 52. A suitable cover 55 is applied to the head structure 5 for protecting the ends of the piston rod 32.

The valve structure 23 is constructed to 110 operate the rotary valve body 10 in proper timed relation to produce four cycle operation of the engine through the proper control of the ignition of gaseous mixture to the opposite sides of the piston 38 for compression, ignition, expansion and exhaust through the well known cycle of operation of a four cycle internal combustion engine. In this way a single cylinder and piston engine construction for internal combustion 115 engines has been provided in which power impulses are applied to the opposite sides of the piston in alternate time relation in order to increase the power output with a larger number of power impulses and at the 120 same time providing a more continuous and uniform application of power.

A particular feature of the invention resides in the piston construction including the manner of mounting the piston on the 125

piston rod and the lubrication of the same as illustrated particularly in Fig. 2 together with the cooperating bearing structures 34 and 34 for the piston rods in order to insure 5 a gas-tight joint with the rod at the end of the cylinder. A further features is the manner of feeding oil to the passage 46 in the piston rod in the manner as illustrated in Figs. 1 and 3 and in addition the particular 10 assembly of the cylinder blocks, crank case structure, and head structure 5 by a single assembling means.

A further feature of the invention resides in the assembly of the head structures with 15 the cylinder blocks and in the crank case and the relation of the rotary valve structure therewith in providing a simple and efficient mounting for this rotary valve in a manner to permit the easy assembly or disassembly 20 thereof from the engine.

The rotary valve member 10 is of hollow construction as illustrated in Fig. 4 of the drawings, from which it will be noted that the heat of the combustion gases will be distributed over the surface of the hollow cylinder forming the body of the valve and to the intake passages through the valve that the mixture being drawn through this valve construction, will cool the same, thus heating 25 the gases entering the combustion chamber and increasing the efficiency of the engine. In addition, some of the heat is distributed to the surrounding part of the cylinder block which is water cooled, so that it will be readily understood that this valve mechanism 30 is maintained at a cool condition at all times and even expansion through the equal distribution of the heat in order to prevent the difficulties in the practical operation of the 35 engine from this cause.

The rotary valve structure which is shown 40 in a substantially vertical position, it is to be understood, may be used in a horizontal position in a vertical engine as well as in a horizontal position in a horizontal engine with equal facility and advantages as above 45 set forth for the structure shown in the drawing where the valve is shown substan-

tially vertical and used with a vertical cylinder.

Having thus described my invention what I claim as new is:—

1. A double acting four cycle internal combustion engine, comprising a cylinder body formed with a cylinder opening through opposite ends of said body, and a cylindrical opening formed in spaced parallel relation to the cylinder, cylinder heads removably secured to the opposite ends of the cylinder body, a piston rod having slidable bearings 50 in engagement in said cylinder heads, and extending axially through the cylinder, a rotary cylindrical valve mounted in the cylindrical opening in the cylinder body, bearings for said valve mounted in the cylinder 55 heads, and means operable by the engine for rotating said cylindrical valves in a predetermined timed relation for controlling ports formed in the cylinder body communicating with the opposite end of the cylinder 60 therein in a predetermined manner.

2. In combination, a cylinder block formed with a cylinder opening through opposite ends thereof and a cylindrical opening parallel to said cylinder, said cylinder block 75 being formed with passages at opposite ends communicating with the cylinder and the cylindrical opening, said cylinder block having one wall thereof formed with a single exhaust opening and a pair of intake openings in aligned relation communicating with the cylindrical opening at diametrically opposite points with respect to the passages, and a cylindrical valve member rotatable in 80 said cylindrical opening and formed with two pairs of passages arranged in substantially right angular relation and extend angularly thru said valve body for alternately providing communication between one 85 of said intake openings and the exhaust opening with opposite end of said cylinder, through the passages formed in said cylinder block.

In testimony whereof I affix my signature.

MICHAEL G. KOURY.
